TUNNEL FORMING APPARATUS

James M. Bankston, Tulsa, Okla.

Application August 27, 1954, Serial No. 452,535

1 Claim. (Cl. 255—20)

This invention relates to an apparatus for use in underground excavating work and particularly appertains to an apparatus for use in forming underground passages or tunnels for the reception of utility pipes or the like piping.

The primary object of this invention is to provide an apparatus for forming underground tunnels without breaking up the surface and in a manner so as not to interfere with passage over the surface above the tunnel.

It is conventional practice in the laying of underground pipes for various uses that the ground is excavated from the surface to the desired depth by digging a trench. Such practice, however, entails the stoppage of traffic over the surface and necessitates repaving and the like surfacing operation after the trench is refilled.

The present invention contemplates the provision of an axially movable driving means which forces a driving tube, of a diameter slightly in excess to that of the pipe to be installed, into the ground at the desired depth and parallel to the surface and the provision of a vibrating means operating on the driving tube to assist in the forward penetration thereof.

The present invention additionally contemplates the provision of an axially movable trolley, which is reciprocated by a reversible prime mover, and which carries an earth boring member that is vibrated by a means carried by the trolley.

Thus, another object of this invention is to provide a carrier which is reciprocated in a rectilinear path by a reversible prime mover and which carries a vibrated earth boring member that tunnels under the ground.

The invention further contemplates the provision of a reciprocable trolley which is moved to and fro on a stationary frame by an endless chain, powered by a reversible prime mover, and which carries a forwardly projecting earth boring tube, that is vibrated in its forward earth boring movement and rearward retracting movement by a means carried by the trolley.

These and ancillary objects are attained by this invention, the preferred embodiment of which is set forth in the following description and illustrated in the accompanying drawings, wherein:

Fig. 1 is a side elevational view of the apparatus, showing the same in use;

Fig. 2 is a view in perspective of the apparatus, and,

Fig. 3 is a front elevational view of the apparatus.

Referring now more particularly to the drawings, the numeral 10 designates a standard or conventional road surface, at the side of which a standard curbing 12 is provided. Outwardly of the road surface, there is a standard parking surface 14. Considering that it is desired to lay pipes under the road surface, it is conventional practice to break up the paving or surface and excavate a trench across the road surface. Such excavation is not only costly but it involves a stoppage of traffic, or, at best, a detour thereof across the road surface and, further, entails a resurfacing of the road surface.

2

With the present invention, it is only necessary to dig a trench 16 in the parking surface 14 and to dig an opening in the parking surface on the opposite side of the road surface. The trench 16 is excavated to the depth at which the desired pipes are to be laid and at a width and length commensurate to receive the apparatus 18, which is lowered into the trench and raised therefrom by any suitable means.

The apparatus 18 includes a base frame, which is composed of longitudinal, spaced apart bottom side bars 20, which are in the form of angle irons and are transversely connected by cross bars 24. The side bars 20 and 22 constitute tracks which support a mobile trolley, as will be described. Standards 26 upstand from the side bars 20 and 22 and are attached at their upper ends to top side bars 28. Such top bars 28 have upwardly inclined forward ends which are attached to a vertical front frame 30 which is disposed transversely between the top and bottom side bars. Suitable diagonal brace bars 32 are provided to rigidify the frame work. The front frame 30 includes a top wall 34, side walls 36 and 38 and a front wall 40. A foot member 42 is transversely carried by the lower end of the front wall, which is formed with a vertically elongated, rectangular opening 44.

The cross bars 24 are disposed under the bottom side bars and form ground supports for the frame work. In this respect, leveling means is carried by the front frame 30 for raising or lowering the front end of the frame work. Such means includes a pair of apertured ears 46 and 48, which project laterally from the opposite side edges of the top wall 34. Securely depending from the ears, in registry with the apertures therein, are tubes 50 and 52, which are vertically secured, as by welding, to the side walls of the front frame. A foot bar 54 is positioned transversely under the bottom side bars and has upstanding rods 56 and 58 provided adjacent its ends, the rods being sleeved through the tubes and being axially slideable therein. A bar 60 connects the upper ends of the rods and is formed with a threaded, collar type, opening 62 in which a screw rod 64 is threaded. The rod 64 is threaded into a reinforced, threaded opening 66 in the top wall 34 and, by virtue of such connection, is adapted to raise and lower the front frame, a crank 68 being provided on the rod 64 for manually effecting such adjustment.

A carrier or trolley 70 is supported by the side bars 20, the trolley having wheels 72 which roll on the inwardly turned horizontal flanges of the side bars inside the vertical flanges thereof. The trolley is reciprocated on the side bars 20, which form tracks therefor, by a reversible air motor 74. The motor 74 is vertically mounted on a suitable platform 76 which is carried by the top side bars 28 at their rear ends. A chain speed reduction unit 78 is carried by the platform and connected to the motor by a suitable chain drive transmission arrangement.

A pair of longitudinally extending, transversely spaced driving chains 80 and 82 are provided and are disposed on opposite sides of the trolley 70. The chains have their forward ends entrained on sprockets 84 which are circumposed on a shaft 86. The shaft 86 has its ends suitably journaled in the side walls 36 and 38 of the front frame and is disposed transversely therebetween. The rear ends of the chains are entrained on drive sprockets 88, which are driven by a suitable drive transmission means from the reduction unit 78. The bottom reaches of the chains are attached to the opposite sides of the trolley 70 and, as the chains are rotated, the trolley is reciprocated to and fro on the tracks.

The motor 74 is powered by compressed air, supplied by the hose 90 from any suitable remote source. The hose 90 is attached to a T-fitting 92, to one end of

which a valve block 94 is connected. Pipes 96 and 98 extend from the valve block to the motor and the admission of air thereto is controlled by hand valves 100 and 102. The pipe 96 constitutes the forward air supply carrier for the motor, while the pipe 98 constitutes the return air supply carrier.

The opposite end of the T-fitting 92 is attached to a flexible hose 104 which is connected to the rear end of the trolley 79 and supplies air for the pneumatic jack or air hammer 106 carried by the trolley. To the jack 106, that is the externally projecting portion thereof, a driving tube section 108 is attached in end to end relation. The outer end of the tube section 108 carries a driving point 110 which penetrates the earth in a boring fashion. A hand valve 112 is provided to control the admission of air to the jack or hammer.

In use, the apparatus 18 is lowered into the trench 16 and, by virtue of the leveling means it set at the desired horizontal plane of attack into the ground underlying the road surface 10. Of course, prior to the use of the apparatus, the trench 16 and an opening in the parking on the opposite side of the road surface have been made. When the apparatus is in place, the valve 100 is operated to admit compressed air to the motor 74, whereby the trolley is propelled forwardly by the moving chains. The driving tube section 108 is forced forwardly driving the point 110 into the earth. At the same time, the valve 112 is operated to admit air to the jack or hammer so that the trolley is urged forward and the point 110 is held under compression, the air hammer vibrating the driving tube. Thus, as the point is hammering into the earth, the trolley is being urged forward to form a back-up.

When the lead-off section 108 is driven into the earth to the point where the trolley can no longer move forward, the section is released from the trolley and another section is coupled between the trolley and the lead-off section. In such fashion, the operation is continued until the driving point breaks through into the opening on the opposite side of the road surface.

When the tunnel is completely formed by the break through into such opening, the tube sections are withdrawn from the tunnel by the retractive movements of the trolley. Assisting in such retraction is the jarring action of the air hammer.

It can be seen that an important feature of this invention resides in the combined action of the reciprocable trolley and the air hammer arrangement for, as the trolley pushes forwardly on the driving tube section, the hammering action causes the driving point to bore into the earth and, as the trolley pulls the sections out from the

tunnel, the jarring action aids in the dislodgment of the sections.

While the best known form of my invention has been shown and described, other forms may be realized as come within the scope of the invention defined by the appended claim.

What is claimed is:

An apparatus for forming underground substantially horizontal tunnels for the reception of pipes and the like; said apparatus comprising a stationary, horizontally disposed base frame, longitudinally extending, laterally spaced guide tracks on the frame, a carriage having wheels rotatably disposed on the guide tracks for moving the carriage longitudinally of the frame, a base plate transversely underlying one end of the frame, rods upstanding from said plate at both sides of the frame, tubular means vertically carried by the sides of the frame and in which said rods are sleeved, a cross bar overlying the frame and connecting the upper ends of the rods, an adjusting screw threaded through the cross bar and rotatably seated on the frame for raising and lowering the one end of the frame relative to the base plate, shafts rotatably mounted transversely of the frame and adjacent the ends thereof, sprocket wheels fixed on the shafts, endless chains entrained over the sprocket wheels and connecting the shafts, means securing one reach of the chains to the carriage so that the carriage is reciprocated back and forth by the rotation of the chains, a reversible air motor mounted on the frame, drive means connecting the motor to one of the shafts, forward and reverse air pipes connected to the motor and upstanding therefrom, valve means connected to the upper ends of said pipes, an air hammer carried by the carriage and extending axially therefrom toward said one end of the frame, a flexible air hose arranged alongside the first named valve means and connected to the hammer, valve means connected to the hose and a detachable earth boring element attached to the extending end of the air hammer.
